PULVERIZER

Franklin M. Iler, Cleveland, Ohio; Eleanor C. Iler
administratrix of said Franklin M. Iler, deceased

Application June 6, 1932, Serial No. 615,545

3 Claims. (Cl. 83—10)

The present invention relates to pulverizers or crushers adapted to reduce rock or other crushable material to a very fine pulp or powder, and more particularly to a rotary disc pulverizer in which the discs are given an oscillating movement relative to each other in addition to their relative rotational movement.

An object of the present invention is the provision of a novel pulverizer of the type referred to which will be simple in construction, and substantially dust-tight, thereby preventing the escape of dust during operation.

Another object of the invention is the provision of a novel pulverizer of the type referred to, provided with means for adjusting the discs relative to each other whereby the fineness of the pulp may be varied, and a forced lubrication system for the various bearings whereby the life of the machine may be extended.

Another object of the present invention is the provision of a novel oiling system for the various bearings of a pulverizer of the type referred to. The invention resides in certain novel details of construction and combinations and arrangements of parts, and further objects of the invention will be apparent to those skilled in the art from the following description of the preferred embodiment thereof described with reference to the accompanying drawings, in which

Fig. 1 is a side elevation of a pulverizer embodying the present invention with the hopper shown in dotted lines in its elevated position;

Fig. 2 is a plan view of the machine shown in Fig. 1 with the dust covers removed to show the interior thereof;

Fig. 3 is an end elevation of the machine shown in Figs. 1 and 2 with the hopper in its elevated position;

Fig. 4 is a view similar to Fig. 1 with portions broken away to illustrate the arrangement of the various parts;

Fig. 5 is a section approximately on the line 5—5 of Fig. 4, and

Fig. 6 is a section on the line 6—6 of Fig. 1.

Similar reference characters designate corresponding parts throughout the several figures of the drawings.

Referring to the drawings the main frame or base of the machine is indicated in general by the reference character 10. A main drive shaft 11 rotatably supported in bearings 12 and 13 formed in opposite ends of the frame 10 carries a revolving disc 15 secured as by three bolts 16 to a flanged collar 17 fixed to one end of said shaft, and tight and loose pulleys 18 and 19, respectively, on the other end thereof. As illustrated the machine is adapted to be driven by a belt, but it is to be understood that other well known means may be employed for driving the shaft 11. An oscillator member 20 pivotally sup-

ported at the rear or right hand end of the machine, as viewed in Figs. 1, 2 and 4, on pivot pins 21 secured in suitable apertures provided in bosses 22 on the frame 10 is adapted to be oscillated about the axis of the pivot pins 21 by connecting rods 23, as will be hereinafter described. The oscillator member 20 is guided near the front end thereof by the engagement of guide members 24 formed integral therewith with guide surfaces 25 formed on the frame 10.

A hopper member 28 pivotally supported on a hopper hinge pin 29 secured in a boss 30 on the top of the oscillator 20 is adapted to be moved from its operating position, shown in full lines, to an inoperative position, shown in dotted lines, see Fig. 1. A stationary disc 31 provided with a crushing surface 32 adapted to cooperate with a crushing surface 33 on the rotating disc 15 is secured to the hopper 28 as by the bolts 34. The hopper is held in its operating position by the eye 20 bolts 35 secured to the oscillator 20 as by the pins 36, and burr nuts 37 threaded on the eye bolts 35 and engaging lugs 38 formed integral with the hopper. The crushing surfaces 32 and 33 are curved and preferably lie in the surface 25 of a sphere, the center of which is the intersection of the axis of the main shaft 11 and the axis about which the oscillator is pivotally supported. The central part of each disc is hollowed out to provide a receiving chamber for 30 the material to be pulverized and the side walls of the receiving chamber are provided with ridges 40 and grooves 41 to facilitate the pulverizing operation. A projection 42 on the hopper 28 has a channel 43 formed therethrough which communicates with the material receiving chamber formed by the discs and through which the material to be pulverized is introduced. A cover 44 positioned over the channel 43 prevents the escape of dust. A pulp pan 46 secured to the bottom of the hopper 28 by spring members 47 receives the pulverized material and forms a dust-tight closure for the lower part of the chamber formed by the parts of the oscillator and hopper members which enclose the discs 15 and 31, etc. 45 A cover plate 48 secured to the oscillator 20, as by the screws 49, forms the rear wall of the last mentioned chamber. A slot 50 in the plate 48 permits pivotal movement of the oscillator 20 relative to the shaft 11.

A worm 54 provided with a thrust collar 55 formed integral therewith is fixed to the main shaft 11 and the revolving disc 15 is adjusted toward and from the stationary disc 31 by rotating an adjusting collar 56 which abuts and forms a stop for the thrust collar 55. The adjusting collar 56 is threaded onto a boss 57 formed on the frame 10 coaxial with the shaft 11 and is retained in any adjusted position by an adjusting handle 58 adapted to be threaded into any one of 60

a plurality of tapped holes 59 in a flange 60 formed integral with said collar. A lead plug 61 at the bottom of the holes 60 prevents injury to the threads on the boss 57 and retains the collar 56 in any adjusted position when it is forced against said threads by the handle 58. A rear cover 62, see Figs. 1 and 6, on the right hand end of the oscillator 20 as viewed in Figs. 1, 2 and 4 affords access to the rear end of the frame 10 and is provided with a slot 63 through which the handle 58 projects. The slot 63 is closed by a sliding dust cover 64 which may be rotated 180° from the position shown in Fig. 6 when the handle 58 is moved to the other side of the center line of the machine.

A worm wheel 68 provided with eccentric hubs 69 is rotatably mounted on a shaft 70 supported by the frame 10, and is continuously in mesh with the worm 54. The lower ends of the connecting rods 23, previously referred to, are mounted on the eccentric hubs 69 of the worm wheel 68. From the construction just described it will be apparent that the oscillator 20 will be moved about its pivotal axis upon rotation of the shaft 11 through the worm gear 54, worm wheel 68 and connecting rods 23. An opening 72 in the front part of the oscillator 20 is covered by a dust cover 73.

Front and rear oil recesses or channels 75 and 76 respectively, are formed in the frame 10 directly above the bearings 12 and 13 and have passages 77 communicating therewith and with said bearings. Apertures 71, one of which is shown in Fig. 4, communicates with the guide surfaces 25 on the frame 10 and delivers oil thereto from the channel 75. Oil from the oil reservoir in the bottom of the frame is pumped to the channel 76 by an oil pump and flows from the channel 75 to the channel 76 by gravity through a tube 78 communicating with said channels. The height of the oil in the channels 75 and 76 is determined by overflow apertures 79 formed in the sides thereof. The oil pump referred to comprises a hollow rod 80 having a longitudinal passage 81 slidably positioned in a cylindrical bore 83 in the frame 10. The passage 81 is closed at its upper end by an adjustable screw 82 threaded in the rod 80 and locked in any adjusted position by a lock nut 83a, and at its lower end by a ball valve 84 adapted to engage a valve seat formed at the lower end of said rod. The rod 80 is continuously urged in an upward direction by a compression spring 85 positioned in the lower part of the bore 83 and is reciprocated in said bore by the engagement of the head of the screw 82 with an abutment 87 on the oscillator 20 upon movement of said oscillator about its pivotal axis. An opening or port 89 formed in the frame 10 communicates with the oil reservoir in the bottom of the frame and the bore 82 just below the lower end of the rod 80 when the said rod is in its uppermost position. An opening or port 90 also formed in the frame 10 communicates with the channel 75 and the passage 81 through a recess 92 formed about the rod 80 and an aperture 93 in said rod communicates with said recess and the passage 81. The construction of the oil pump is such that when the rod is in its extreme upper position the port 79 is open and oil flows from the reservoir into the bottom of the bore 82, as the rod 80 descends under the action of the oscillator 20 the port 79 is closed thereby, and the oil in

the bottom of the bore is forced past the valve 84, through the passage 81, the aperture 93, the recess 92, and the port 90 into the chamber 75.

The preferred embodiment of the invention has been illustrated and described, but I do not wish to be limited to the particular construction shown, which may be varied within the scope of this invention, and I particularly point out and claim as my invention the following:

1. In a machine of the character described, the combination of a frame, a plurality of bosses formed integral with said frame, a shaft rotatably supported in said bosses, a pulverizing disc carried by said shaft, a member pivotally supported by said frame, means operatively connected to said shaft for oscillating said member about its pivotal support upon rotation thereof, a second pulverizing disc carried by said member cooperating with the first mentioned pulverizing disc, said frame being provided with an oil reservoir in the base thereof and a plurality of oil receiving recesses above said bosses, a tube connecting said oil receiving recesses, means for delivering oil from said recesses to the bearings for said shaft, a reciprocating pump for pumping oil from said reservoir into one of said oil receiving recesses, and means for operatively connecting said pump and said member whereby said pump is actuated by the oscillation of said member.

2. In a machine of the character described, the combination of a frame, a plurality of bosses formed integral with said frame, a shaft rotatably supported in said bosses, a disc provided with a central recess carried by said shaft, a member pivotally supported by said frame, means operatively connected to said shaft for oscillating said member about its pivotal support upon rotation thereof, said disc having a crushing surface lying in the surface of a sphere the center of which is on the axis about which said member is pivotally supported, a second disc supported by said member, a crushing surface on said second disc cooperating with the first mentioned crushing surface, a hopper carried by said member and communicating with said recess, said frame being provided with an oil reservoir in the base thereof and a plurality of oil recesses above said bosses, a tube communicating with said oil recesses, means for delivering oil from said recesses to the bearings for said shaft, a reciprocating pump for supplying oil to one of said recesses from said reservoir, and means for operatively connecting said pump and said shaft whereby said pump is actuated upon the rotation of said shaft.

3. In a machine of the character described, the combination of a frame, a shaft rotatably supported by said frame, a pulverizing disc carried by said shaft, a member pivotally supported by said frame, means operatively connected to said shaft and said member for oscillating said member about its pivotal support upon the rotation of said shaft, a second pulverizing disc carried by said member cooperating with the first mentioned pulverizing disc, said frame being provided with an oil reservoir in the base thereof and an oil receiving recess near the top thereof, means for delivering oil from said recess to the bearings for said shaft, a pump supported by said frame for pumping oil from said reservoir into said oil receiving recess, and means on said pivotally supported member for operating said pump.

FRANKLIN M. ILER.
